Primary Examiner — Leanne Was-Englehart(74) *Attorney, Agent, or Firm* — Lawrence J. Gibney, Jr.; Mitchell Ghaneie(57) **CLAIM**

The ornamental design for curved gate, as shown and described.

DESCRIPTION

FIG. 1 is a front elevational view of a curved gate showing my new design;

FIG. 2 is a back elevational view thereof;

FIG. 3 is a left side elevational view thereof;

FIG. 4 is a right side elevational view thereof; and

FIG. 5 is a top elevational view thereof;

FIG. 6 is an isometric view thereof; and,

FIG. 7 is an in use view of the device.

The broken lines depict portions of the environment that form no part of the claimed design.
